CLAIM

The ornamental design for a lip suction device, as shown and
described.

DESCRIPTION

FIG. 1 is a top plan view of a lip suction device showing our
new design.

FIG. 2 is a bottom plan view of the lip suction device.

FIG. 3 is a right side elevational view of the lip suction
device; the left side elevational view is a mirror image of the
right side elevational view.

FIG. 4 is a front elevational view of the lip suction device.

FIG. 5 is a back elevational view of the lip suction device.

FIG. 6 is a front perspective view of the lip suction device.

FIG. 7 is a side perspective view of the lip suction device.
FIG. 8 is a top perspective view of the lip suction device;
and,

FIG. 9 is a bottom perspective view of the lip suction device.
The broken lines in the drawings depict parts of the lip
suction device that form no part of the claimed design.
